SAFETY PIN

Henry Burbig, New York, N. Y.

Application June 22, 1948, Serial No. 34,402

5 Claims. (Cl. 24—161)

1

This invention relates to a safety pin.

An object of this invention is to provide a safety pin in which the point is guarded in all normal unstrained positions of the pin.

Another object of the invention is to provide a safety pin which has no projecting portions or exposed notches in either its closed or latched position or in its normally open position. For example, even if the pin of the present invention should be accidentally swallowed, the point whether open or latched, would not be exposed to pierce and there are no gouging portions and no wedged shaped notches or slots to catch on or scratch the internal parts of the body.

Another object of the invention is to provide a safety pin with an internally situated keeper or locking means.

Another object of the invention is to provide a safety pin in which the pointed prong can only be exposed for piercing by applying pressure to push it away from its protecting shield.

These and other objects ancillary thereto are obtained by forming a safety pin with a pointed wire prong situated within a wire framework. The end of the framework adjacent the point of the prong contains a guard or shield which includes an internally situated lock or keeper. The guard or shield is so constructed as to permit springing the pointed prong perpendicularly away from the framework in both directions or in one direction only. The end of the framework opposite the point may contain a metal cover for reinforcing and enclosing the said end. The keeper or latch which is within the shield is preferably slightly spaced away from the exact center of the framework so that when the point is sprung into the keeper it is held against the inner edge of the keeper and so that the point when outside of the keeper is not forced above or below the guard by the outer edge of the keeper.

The novel features characteristic of this invention are set forth with particularity in the appended claims. The invention itself, however, both as to its organization and its method of operation, together with additional objects and advantages thereof, will best be understood from the following description of specific embodiments when read in connection with the accompanying drawing in which:

Figure 1 is a front or top view of the pin.

2

Figure 2 is a rear or bottom view of the pin.

Figure 3 is a sectional view taken on line 3—3 of Figure 1.

Figure 4 is a sectional view taken on line 4—4 of Figure 2.

Figure 5 is a front or top view of a modified form of the pin.

As shown in the drawing, the prong or pin member 10 has a point 11 and substantially bisects the space between a wire frame. The frame comprises two side members 12 and 13. The frame and prong are conveniently made from one length of wire material by bending at 14 and 15 as shown in Figures 1 and 2. The end of the pin remote from the point has a shield 16 secured thereto which reinforces the end of the pin and provides a smooth surface for that end of the wire frame.

The end of the framework adjacent the point 11 has a housing 20 extending thereabout. The inner top edge 21 of the housing 20 extends over the tip of the point 11 of the prong 10. The inner bottom edge of the housing 20 is divided into two portions. A first portion 22 extends considerably beyond the tip of the point 11. The second edge portion 23 is indented or cut away sufficiently to permit the point 11 to be forced outwardly away from the frame past the said edge 23.

At least partly within the housing 20, the keeper 25 is formed. One edge of this keeper 25 is substantially continuous with the edge portion 22. This keeper 25 is preferably formed by slitting the bottom of the housing 20 along the edge 23 and bending the tongue so formed in the shape of a J which is situated at least partly within the housing 20. The extent to which the edge 21 extends over the pin point and over the keeper 25 is a matter of choice. It can be made to extend entirely over the keeper 25; however, since one end of the keeper is always within the housing, and is thus shielded from contact with any flat surface, it is not necessary to make the edge 21 extend entirely over the keeper 25.

The inner edge of the keeper is preferably spaced just slightly away from the center of the housing 20 so that in latched position there is a tendency for the point 11 to rest firmly against the inside of the bend of the keeper 25, and so that in unlatched position the prong is not forced outside of the indented edge portion 23. As

shown in Figures 3 and 4, the open edge of the J of the keeper 25 can extend fairly close to the top edge 21 of the housing 20 so that the prong 10 must be snapped past the space between the keeper 25 and the edge 21.

As shown in Figure 4, even when the point of the prong 10 is not inserted in the keeper, it is shielded by the housing 20 so as to prevent it from piercing any flat or reasonably flat surface with which the pin comes in contact. The pin of this invention can even be swallowed without any great damage to the victim as the point is shielded even in its unlatched position and there are no exposed points, projecting edges, notches or gouging elements present on the pin either in the frame members 12 and 13, on the pin 10 itself or on the shields 16 and 20.

As shown in the modification of Figure 5, the housing 20' can be so constructed that the prong 11 can be pushed perpendicularly away from the frame 12, 13 in either direction. In Figure 5 the edge 21' of the housing 20' is not curved inwardly toward the point as the said edge 21' passes the keeper 25' so that the point of prong 11 can pass the lower part of the edge 21' in the same way that it passes edge portion 23. Various other slight changes in the shape of the edge portions are possible without departing from the spirit of the invention but preferably the inner edge portion of the keeper 25' is always overshadowed by the edge 21' and preferably the line running from edges 22 to 21' to 23 is always smooth and continuous with only the one stepped portion where the keeper 25' is formed.

In use the pin can be opened only by a person of relatively mature age by holding the framework firmly against the first two fingers of one hand, for example, and pressing the point 11 past the edge 23 and between the two fingers with the thumb. In this position the point 11 and prong 10 are ready to be inserted into the object that it is desired to pin. After the prong 10 has been threaded in and out of a fabric and then released, the prong 10 will assume a position in back of the shield 20 (if the bite in the fabric is not too large). In any event, the point 11 can be pushed into the keeper 25 and the fabric material on the prong 10 is clamped between the frame members 12 and 13. Any pulling on the fabric which is pinned serves only to hold the prong 10 more tightly against the keeper 25.

I claim:

1. In a safety pin, a pointed prong, a frame extending entirely around said pointed prong, a housing surrounding the end of the frame adjacent the point of said prong, means at the opposite end of the frame fixedly securing the base of the prong to the side members of the frame, said housing having a smooth uninterrupted top surface extending between and substantially contiguous with the sides of the frame, said housing having a smooth bottom surface with a slightly irregular inner edge, one side of said bottom surface of the housing being indented to permit the point of the prong to pass, the other side of the inner edge of the housing defining at least a part of a keeper mechanism, the said indented side of the bottom edge extending to the central part of the housing adjacent the area normally occupied by the point of the prong when the said prong is relaxed whereby the point of the relaxed prong normally occupies the space between the top and bottom surfaces of said housing.

2. In a safety pin, a pointed prong, a frame

extending entirely around said pointed prong, a housing surrounding the end of the frame adjacent the point of said prong, means at the opposite end of the frame fixedly securing the base of the prong to the side members of the frame, said housing having a smooth and uninterrupted top surface extending between and substantially contiguous with the sides of the frame and extending inwardly beyond the point of said prong, said housing having a smooth bottom surface with a slightly irregular inner edge, one side of said bottom surface of the housing being indented to permit the point of the prong to pass, the other side of the inner edge of the housing defining at least a part of a keeper mechanism, the said indented side of the bottom edge extending to the central part of the housing adjacent the area normally occupied by the point of the prong when the said prong is relaxed whereby the point of the relaxed prong normally occupies the space between the top and bottom surfaces of said housing.

3. In a safety pin, a pointed prong, a frame extending entirely around said pointed prong, a housing surrounding the end of the frame adjacent the point of said prong, means at the opposite end of the frame fixedly securing the base of the prong to the side members of the frame, said housing having a smooth and uninterrupted top surface extending between and substantially contiguous with the sides of the frame, the bottom surface of said housing also extending between the frame members and having a smooth outer surface, the bottom of said housing ending in an edge consisting of two parts, the first part of said edge being indented to permit the point of said prong to move past the same, the second part of said bottom edge extending inwardly beyond the point of said prong, a tongue integral with the portion between the two edges of said bottom of the housing, said tongue being bent to a position within the planes defined by the top and bottom surfaces of said first housing to form a keeper for the point, the said indentation of the bottom edge extending to the central part of said housing and adjacent the area normally occupied by the point of the prong when the said prong is relaxed whereby the point of the relaxed prong normally occupies the space between the top and bottom surfaces of said housing.

4. In a safety pin, a pointed prong, a frame extending entirely around said pointed prong, a housing surrounding the end of the frame adjacent the point of said prong, means at the opposite end of the frame fixedly securing the base of the prong to the side members of the frame, said housing having a smooth uninterrupted top surface extending between and substantially contiguous with the sides of the frame and extending inwardly beyond the point of said prong, the bottom surface of said housing also extending between the frame members and having a smooth outer surface, the bottom of said housing ending in an edge containing two parts, the first part of said edge being indented to permit the point of said prong to move past the same, the second part of said bottom edge extending inwardly beyond the point of said prong, a tongue integral with the portion between the two edges of said bottom of the housing, said tongue being bent to a position within the planes defined by said top and bottom surfaces of said housing to form a keeper for the point, the said indentation of the bottom edge extending approximately one half of the distance between the sides of the frame

and adjacent the area normally occupied by the point of the prong when the said prong is relaxed whereby the point of said relaxed prong normally occupies the space between the top and bottom surfaces of said housing.

5. The device of claim 4 in which the frame and prong are made from a single length of wire.

HENRY BURBIG.
